UNITED STATES PATENT OFFICE.

MORRIS SIGMAN AND MATTEO DE CESARE, OF NEWARK, NEW JERSEY, ASSIGNEES TO
MICHAEL RABB, OF NEWARK, NEW JERSEY.

SOUND-EMISSION DEVICE.

Application filed December 19, 1922. Serial No. 607,800.

To all whom it may concern:

Be it known that we, MORRIS SIGMAN, a citizen of the United States, and MATTEO DE CESARE, a subject of the King of Italy, residing at Newark, in the county of Essex and State of New Jersey, have invented certain new and useful Improvements in Sound-Emission Devices; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in sound emitting devices for toys; and the invention has reference, more particularly, to an improved speaking device for talking dolls whereby the character of the emitted sound is automatically controlled and articulated.

The invention has for its principal object to provide a novel improved sound emitting or speaking device for dolls and similar toys in which an automatic or weight actuated bellows or air compression means is provided with a sound producing reed arrangement, a flap valve for controlling the sound emitted by the reed arrangement, and a novel construction and arrangement of flap valve tripping means whereby the same is actuated to cause an articulation of the emitted sound.

The invention has for a further object to provide a novel enclosing casing for the sound emitting or speaking device, including novel means for securing the latter to and in proper attached supported relation to the casing, all to the end that a strong, durable, easily and cheaply manufactured and efficient complete device is afforded for the purposes in view, and one which is little likely to become accidentally injured or disarranged from normal operative condition when mounted within dolls or other toys likely to be subjected, in the hands of children, to more or less rough handling.

Other objects of this invention, not at this time more particularly enumerated, will be clearly understood from the following detailed description of the same.

With the various objects of this invention in view, the same consists, primarily, in the

novel sound emitting device for toys herein-after set forth; and the invention consists, furthermore, in the novel arrangements and combinations of the various devices and parts, as well as in the details of the construction of the same, all of which will be more fully described in the following specification, and then finally embodied in the claims appended thereto.

The invention is clearly illustrated in the accompanying drawings, in which:—

Figure 1 is a perspective elevation of the encased sound emitting device made according to and embodying the principles of this invention; Figure 2 is a central vertical longitudinal section through the same; Figure 3 is another central vertical longitudinal section taken on a transverse plane at right angles to the plane of Figure 2; Figure 4 is a vertical section through the casing with the interior sound emitting mechanism shown in elevation, the device in this view being shown inverted to permit the air compression means or bellows to expand by gravity and the sound emitting and controlling elements to be set for operation; Figure 5 is a view similar to that shown in Figure 4, the device, however, being reverted to permit the compression of the bellows by gravity and to thereupon actuate the sound emitting and controlling elements; Figure 6 is a horizontal section taken on line 6—6 in Figure 3; Figure 7 is a bottom plan view of a bellows anchor or coupling plate; Figure 8 is a horizontal section taken on line 8—8 in Figure 2; Figure 9 is a bottom view of the complete device; Figure 10 is a fragmentary detail vertical section showing the method of attaching the flexible bellows body to the upper bellows head; Figure 11 is a similar fragmentary detail vertical section showing the method of attaching the flexible bellows body to the lower bellows head; and Figure 12 is an edge elevation of the valve flap of the sound controlling means.

Similar characters of reference are employed in all of the hereinabove described views, to indicate corresponding parts.

Referring now to said drawings, the reference character 13 indicates a suitable base adapted to form the bottom head of the air compressor or bellows element of the device. Said base or bottom head 13 is preferably made of heavy card-board, although it may be made of any other suitable ma-

terial if desired. Connected with the under-side of said base or bottom head is an anchor or coupling plate 14, the same being made of comparatively thin sheet metal, such e. g. as tin. The diameter of said anchor or coupling plate 14 approximates the diameter of said base or bottom head 13, and the marginal edge portion of the former is downwardly flared to provide a divergent flange 15, which provides intermediate the same and the adjacent marginal edge portion of the base or bottom head 13 an annular groove or seat 16. Struck upwardly out of the body of said anchor or coupling plate, and in diametric alinement relative to the same, are a pair of prongs or clenching lugs 17 which are thrust upwardly through the base or bottom head and then clenched over the upper or inner side thereof as at 18 (see Figures 3 and 6), to thus firmly secure the base or bottom head and anchor or coupling plate together. In a similar manner, struck downwardly out of the body of said anchor or coupling plate 14, and in diametric alinement at right angles to the prongs or clenching lugs 17, are a second pair of prongs or clenching lugs 19, the purpose of which will be subsequently disclosed. Secured centrally to said base or bottom head 13, so as to extend vertically upward therefrom, is a combined guide and trip member 20, which preferably consists of a flat rigid metallic bar or rod. The lower end of said member 20 is provided with a tongue or extension 21 of reduced width which penetrates said anchor or coupling plate 14, and the exposed extremity of which is secured to the latter by solder 22 (see Figures 2 and 3), thus securely fastening the guide and trip member 20 against displacement from proper attached assembled relation to said base or bottom head 13. Slidable on said combined guide and trip member 20 is the movable upper head 23 of the air compressor or bellows element of the device. Said movable upper head 23 is constructed to possess sufficient weight to cause the same to be readily moved by gravity as guided by the guide and trip member, and to this end the same may be made of substantial thickness out of lead or other comparatively weighty material. Formed in the periphery of said movable upper head 23 is an annular groove or seat 24. The reference character 25 indicates a cylindrical shaped bellows member, preferably made of a suitable flexible material which is impervious to air, such e. g. as thin rubber, oil-silk or other suitably treated flexible fabric material. One end of said bellows member 25 is engaged downwardly over the periphery of said movable upper head 23, so as to extend over the groove or seat 24, whereupon a tie-cord 26 is engaged around the same to draw into and fasten such bellows end into the seat or groove 24, to thus tightly secure said bellows end to the movable upper end, and then the bellows member is reversed and drawn down over the upper head 23 so as to extend downwardly therefrom, all in the manner shown in the drawings, and more especially illustrated in Figure 10 thereof. The opposite end of the bellows member 25 is thereupon engaged over the base or bottom head 13 to extend over the groove or seat 16 intermediate the same and the flange 15 of the anchor or coupling plate 14, whereupon a tie-cord 27 is engaged around the same to draw into and fasten the lower bellows end into the seat or groove 16, to thus tightly secure said bellows end to the base or bottom head 13, all in the manner shown in the drawings, and more especially illustrated in Figure 11 thereof.

Connected with said upper head 23; preferably as an integral part thereof, and disposed so as to project vertically therethrough in off-set position relative to the guide and trip member 20, is a hollow sound-box 28, one end of which projects downwardly into the interior of said bellows or air compressor element, and the opposite end of which projects upwardly and exteriorly above the outer side or top of said upper head 23. The interior or lower end portion of said sound box is closed, but connected in communication with the interior thereof is a sound-producing device or reed-pipe 29, the operative end of which is exposed within the interior of the bellows or air compressor element so as to be actuated by the compression of air within the latter. The exterior end of said sound-box 28 is provided with an orifice or mouth 30, normally closed by means of a flap-valve 31. Said flap-valve is hingedly or pivotally connected with said exterior end of said sound-box so as to swing up and down to open and close said orifice or mouth 30, while at the same time the pivotal connection of the same is of a character permitting a limited lateral play or side to side movement of the same when in closed position relative to the orifice or mouth 30. The pivotal connection for thus mounting said flap-valve comprises a yoke 32 affixed against the outer side of the sound-box 28 by means of a screw 33 or other suitable fastening means, said yoke 32 having at its upper edge a horizontally disposed lateral stationary hinge ear or tubular bearing 34, through which is passed a hinge pintle 35. Said flap-valve 31 is provided at its rear end with a pair of laterally spaced perforate hinge ears 36 adapted to straddle and normally aline themselves with said stationary hinge ear 34, so as to also loosely receive said hinge pintle 35, whereby said flap-valve may swing upwardly away from the orifice or mouth 30.

30 or downwardly into closed relation to the same, while at the same time a certain amount of play between the hinge ears and pintle is allowed for to permit a limited 5 side to side movement or lateral play to the flap-valve when the same is in closed position. In order to yieldably hold said flap-valve in a normal centrally alined extension from its hinge or pivotal connection, 10 and at the same time provide a tension means for returning the same to normal closed position relative to said orifice or mouth 30, a tension means is provided in the form of a resilient endless band 37, which is preferably 15 made of soft rubber, although it may also be made of spring wire if desired. This resilient band is disposed to extend over the flap-valve, thence downwardly around the sides thereof forward of the hinge ears 36, 20 and thence rearwardly around and beneath the stationary hinge ear or bearing 34.

Said flap-valve is provided at its free end, to extend outwardly at one side thereof, with a trip projection or lug 38, the outer 25 portion of its extremity being turned upwardly to provide a downwardly sloping or transversely oblique cam-portion 39.

The upper portion of said guide and trip member 20 is cut away at one side to reduce 30 its width as at 20', and is provided in a proper position with a trip-lug 40 having a downwardly and inwardly chamfered under side 41 and spaced below and alined with said trip-lug 40 is a shoulder 42 formed 35 by the juncture of said reduced portion 20' and the full width portion 20.

Said trip-projection or lug 38 and its cam-portion 39 of the valve-flap is so disposed that its path of movement is alined 40 with said trip-lug 40 and shoulder 42.

The reference character 43 indicates a cylindrical casing which is preferably made of paper-board. The lower end of said casing 43 is closed by a bottom cap 44 suitably secured thereto. The bellows or air compressor element with its sound emitting and controlling devices is inserted within said casing 43, and the prongs or clenching lugs 19 of the anchor or coupling plate 14 45 are caused to project downwardly through the bottom cap 44 and are then clenched over the outer side or bottom thereof as at 19' (see Figures 2, 3 and 9), to thus firmly couple or anchor said plate 14 and base or bottom head 13 to the bottom end of the casing, and consequently securely and firmly holding the bellows or air compressor element with its sound emitting and controlling devices operatively attached to and fixed 50

60 within the casing 43. Connected with the upper end of said casing 43 is a cross-bar 45 extending diametrically across the upper mouth of the casing, said cross-bar 45 having at its respective ends attaching ears or lugs 46 which dove-tail into the walls of

said casing (see Figure 8). The upper free end of said guide and trip member 20 constituted by the reduced portion 20' is engaged in or penetrates said cross-bar 45, thus firmly holding the said upper end 70 against lateral displacement. Engaged over and suitably secured to the upper end of the casing 43 is a top cap 47 the end wall of which is provided with a plurality of perforations 48 permitting the escape of sound waves from within the casing 43.

The encased sound emitting device, constructed as above described, is suitably disposed within the interior of the body of a doll or other toy, usually with the weighted end of the bellows or air compressor toward the head end of the doll. To operate the device the doll is positioned so that the weighty upper head 23 of the bellows element will be moved by gravity outwardly 85 on the guide and trip member 20 to thus expand the bellows element and fill the same with air, while at the same time carrying the trip projection of the flap-valve 31 above the trip-lug 40. This having been done, the doll is raised to revert the sound emitting device so that the pull of gravity will cause the weighty upper head 23 to slide downwardly on the guide and trip-member 20, thus collapsing the bellows element to compress the air within the same, and thereby force the air to pass operatively in an outward direction through the reed-pipe and sound-box. As the weighty upper head 23 moves downward the trip-projection of the 100 valve-flap is carried into passing engagement with the trip-lug 40 of the guide and trip member 20. Said trip-projection is yieldable to pressure in an upward or outward direction against the vertical tension 105 of the resilient member 37, and consequently the flap-valve is temporarily opened and closed, thus permitting the air to escape from the sound-box to produce an emission or ejaculation of sound of short duration 110

115 during the initial stages of the collapse of the bellows element, whereby e. g. the syllable "ma" is produced, as will be understood from an inspection of Figure 5. After the flap-valve is thus temporarily opened and closed, and before the complete collapse of the bellows element, the continued downward movement of the weighty upper head 23 and associated parts carries the trip-projection of the valve-flap 31 past the shoulder 42 into engagement with the main body of the guide and trip member 20, whereby not only is the valve-flap 31 again raised but is held raised during the last 120 stages of the collapse of the bellows element, so that during such period air escapes from the sound-box to produce an emission of sound of comparatively long duration, whereby e. g. the syllable "maa" is articulated. This operation will be understood 125 130

from an inspection of Figure 3 of the drawings. The consequent short ejaculation of the syllable "ma" followed by the longer sounding of the syllable "maa," effects a 5 very life-like articulation of the word "mama."

When inverting the sound emitting device to set the parts preparatory to the operations above described, the stop-projection slides upwardly or outwardly on the main body of the guide and trip member 20 until it passes off of the shoulder 42, whereupon the valve-flap closes, and as the outward movement continues, the trip-projection moves into outward passing engagement with the trip-lug 40, and in so doing the oblique cam-portion 39 of the trip-projection engages the chamfered underside 41 of the trip-lug 40 whereby the flap-valve 20 31 is caused to yield laterally against the horizontal tension of the resilient means 37 to thereby permit the trip-projection to side-step the trip-lug so as to pass the same when resuming position initial to its 25 operative movement in the opposite direction.

We are aware that some changes may be made in the various arrangements and combinations of the several devices and parts, as well as in the details of the construction of 30 the same, without departing from the scope of this invention as set forth in the foregoing specification, and as defined in the appended claims. Hence we do not limit our invention to the exact arrangements and 35 combinations of the various devices and parts as described in said specification, nor do we confine ourselves to the exact details of the construction of parts as illustrated in the accompanying drawings.

40 We claim:—

1. In a device of the kind described, a bellows having a bottom head and a movable upper head, a sound emission device having an outlet orifice carried by said movable upper head and actuated by compression of air in said bellows, a tension controlled pivoted flap valve normally closing said outlet orifice, a combined guide and trip member fixed to said bottom head to extend 45 through said bellows and upper head and upon which the latter is guided, cooperative means on said combined guide and trip member and said valve-flap for actuating the latter, an anchor plate having upwardly 50 directed clenching lugs clenched through said bottom head, a casing surrounding said bellows having a bottom closure, said anchor plate having additional clenching lugs clenched through said bottom closure to couple 55 said bellows to said casing, and a perforate closure at the opposite end of said casing.

2. In a device of the kind described, a bellows having a bottom head and a movable upper head, a sound emission device

having an outlet orifice carried by said movable upper head and actuated by compression of air in said bellows, a tension controlled pivoted flap-valve normally closing said outlet orifice, a combined guide and trip member fixed to said bottom head to extend through said bellows and upper head and upon which the latter is guided, cooperative means on said combined guide and trip member and said valve-flap for actuating the latter, an anchor plate having upwardly directed clenching lugs clenched through said bottom head, a casing surrounding said bellows having a bottom closure, said anchor plate having additional clenching lugs clenched through said bottom closure to couple said bellows to said casing, a perforate closure at the opposite end of said casing, a diametrically extending cross-bar attached at the said opposite 85 end of said casing beneath said perforate closure in which the upper free end of said combined guide and trip member is engaged.

3. In a device of the kind described, a bellows having a bottom head and a movable upper head, a sound emission device having an outlet orifice carried by said movable upper head and actuated by compression of air in said bellows, a tension controlled pivoted flap-valve normally closing said outlet orifice and capable of limited lateral play, a trip-projection at the free end of said flap-valve, said trip-projection having an oblique cam-portion at its free end, a combined guide and trip member fixed to said bottom head to extend through said bellows and upper head and upon which the latter is guided, said guide and trip member having above said movable upper head a portion of reduced width from which projects a trip-lug provided with a chamfered underside engageable by said trip-projection and its cam projection, and said guide and trip member at its full width portion being engageable by said trip-projection to hold 105 said flap-valve in open position.

4. In a device of the kind described, a bellows having a bottom head and a movable upper head, a sound emission device having an outlet orifice carried by said movable upper head and actuated by compression of air in said bellows, a tension controlled pivoted flap-valve normally closing said outlet orifice and capable of limited lateral play, a trip-projection at the free end of said flap-valve, said trip-projection having an oblique cam-portion at its free end, a combined guide and trip member fixed to said bottom head to extend through said bellows and upper head and upon which the latter is guided, said guide and trip member having above said movable upper head a portion of reduced width from which projects a trip-lug provided with a chamfered underside engageable by said trip-projection and its 115 120 125 130

cam projection, said guide and trip member at its full width portion being engageable by said trip-projection to hold said flap-valve in open position, an anchor plate 5 having upwardly directed clenching lugs clenched through said bottom head, a casing surrounding said bellows having a bottom closure, said anchor plate having additional clenching lugs clenched through said bottom 10 closure to couple said bellows to said casing, and perforate closure at the opposite end of said casing.

5. In a device of the kind described, a bellows having a bottom head and a movable 15 upper head, a sound emission device having an outlet orifice carried by said movable upper head and actuated by compression of air in said bellows, a tension controlled pivoted flap-valve normally closing said outlet orifice and capable of limited lateral play, a trip-projection at the free end of said flap-valve, said trip-projection having an oblique cam-portion at its free end, a combined guide and trip member fixed to said bottom 20 head to extend through said bellows and upper head and upon which the latter is guided, said guide and trip member having above said movable upper head a portion of reduced width from which projects a trip- 25 lug provided with a chamfered underside engageable by said trip-projection and its cam projection, said guide and trip member at its full width portion being engageable by said trip-projection to hold said flap-valve 30 in open position, an anchor plate having upwardly directed clenching lugs clenched 35

through said bottom head, a casing surrounding said bellows having a bottom closure, said anchor plate having additional clenching lugs clenched through said bottom closure to couple said bellows to said casing, a perforate closure at the opposite end of said casing, a diametrically extending cross-bar attached at the said opposite end of said casing beneath said perforate closure in which the upper free end of said combined guide and trip member is engaged. 40 45

6. In a device of the kind described, the combination with a bellows and sound emitting and controlling means of a casing to enclose the same, an anchor plate having upwardly directed clenching lugs clenched through the bottom member of said bellows, said anchor plate having additional downwardly directed clenching lugs clenched 50 through the bottom end of said casing to thereby couple said bellows to said casing, and said anchor plate having a flared annular flange at its periphery to provide in conjunction with said bottom member of 55 said bellows an annular groove to seat a tie-cord for fastening the bellows body to its said bottom member. 60

In testimony that we claim the invention set forth above we have hereunto set our 65 hands this 12th day of December, 1922.
